HELMUTH DUEBERG, OF BALTIMORE, MARYLAND.

Letters Patent No. 94,580, dated September 7, 1869.

IMPROVEMENT IN PROGRESSIVE KILNS.

The Schedule referred to in these Letters Patent and making part of the same.

To all whom it may concern:

Be it known that I, HELMUTH DUEBERG, of the city and county of Baltimore, State of Maryland, have invented a new and useful Improvement in Progressive Kilns; and I do hereby declare the following to be a full, clear, and exact description thereof, which will enable those skilled in the art to make and use the same, reference being had to the accompanying drawing, forming part of this specification, in which drawing—

Figure 1 represents a plan or top view of this invention, partly in section.

Figure 2 is a partial longitudinal section of the same.

Figure 3 is a transverse section of the same.

Similar letters indicate corresponding parts.

This invention relates to certain improvements on that class of kilns which is known by the term of "progressive" or continuous kilns, and for which Letters Patent were granted to E. F. Hoffmann, June 13, 1865, and to G. A. Wedekind and myself, December 15, 1868.

The improvements, which form the subject-matter of this present application for a patent, consist in the arrangement of bridges or arches, extending, at suitable distances apart, across the open top of the kiln, and provided with feed-holes, in such a manner that the feed-holes remain permanent while the top of the kiln is changed, and, at the same time, the workmen engaged in operating the kiln, are enabled to walk on the top of said kiln, by stepping on the bridges, without being obliged to come in contact with the temporary cover, which, being highly heated, would be liable to injure their feet.

With the perforated bridges, I have combined tubular furnaces, in which the combustion of the fuel takes place without coming in contact with the material to be burned, and which also serve as props or braces for the bridges.

In the drawing—

The letter A designates a series of burning-chambers, which are arranged in a continuous or endless row, side by side, without, however, being separated from each other by permanent partitions, one movable partition, E, only being used, which is inserted successively between the adjoining burning-chambers to control the circulation of the heated air and products of combustion.

The top of my kiln is partially open, each burning-chamber being provided with one or more bridges, B, which may be flat or arched, and which extend across said chambers, as shown particularly in fig. 2 of the drawing. Through the bridges pass the feed-holes a, which serve to introduce the fuel to be consumed in the several burning-chambers. These feed-holes are either cylindrical, or conical, or trumpet-shaped, and

they may be made to pass through the bridges in a vertical or in an inclined direction.

If the bridges are not supported from below, they must be arched, so as to be self-sustaining, but in most cases it is preferable to apply, below the bridges and under each feed-hole, a cylindrical furnace, C, made of fire-clay, or other suitable refractory material, and perforated with holes to allow access of the air requisite for supporting the combustion of the fuel contained in said furnaces. These furnaces may be permanently fixed under the bridges, or they may be so arranged that they can be readily removed, whenever it may be desirable.

By the use of said cylindrical furnaces, under the bridges, the fuel is not permitted to mingle or come in direct contact with the bricks or other material to be burned, and furthermore, these furnaces occupy comparatively little room, and therefore they do but little interfere with the working capacity of the kiln.

From each burning-chamber extends a flue, F, to the main flue G, which communicates with the smoke-stack, each of the flues F being provided with a separate damper. If the number of burning-chambers is twelve, and the movable partition E is inserted between chambers twelve and one, while all the dampers, except that of chamber twelve, are closed, the top of chamber one is uncovered, all the other chambers being closed and covered, then the cold air passes in through chamber one, and after it has come in contact with and supported the combustion of the fuel, the products of combustion pass off through the flue of chamber twelve.

When the various chambers have been filled with bricks or other material, to be burned, the spaces between the bridges B are closed by layers of tiles, clay, or sand. The furnaces C are supplied with fuel through the feed-holes a, the partition E is adjusted in the desired spot, and the fuel, in the several furnaces, is ignited. If the charge in one of the chambers has been sufficiently burned, it is removed, a fresh charge is introduced, the movable partition is advanced, the spaces between the bridges are again filled with the temporary cover, the dampers are changed, and the operation of burning is continued.

During these operations, the feed-holes, in the bridges B, remain permanent, and always in proper working condition, while the temporary covers have to be removed and replaced with every change of the charge, and the advantages of an open-top kiln are combined with those of a closed-top kiln. The workmen are enabled to walk on the top of the kiln, by stepping on the bridges, without burning their soles, by being compelled to walk over the temporary cover, which becomes highly heated, and when the temporary cover is removed, the kiln cools off rapidly, and

allows the workmen to get inside without difficulty, for the purpose of introducing fresh charges, or for cleaning the chambers, or for other purposes.

My kiln can also be used, with great advantage, for drying green bricks, by setting said bricks up, in the burning-chamber, in piles of such height as the consistency of the green bricks will allow.

After a chamber has thus been charged with green bricks, say to one-half of its height, it is covered by movable covers of sheet-iron, or other suitable material, one of them being laid between each adjoining two bridges; then the waste heat of the fire is allowed to pass through the green bricks for several hours, until said bricks are dried; then the upper-half of the chamber can be filled with green bricks, and finally, the temporary cover of tiles, clay, and sand is put on. According to the consistency of the green bricks, they may be set in two or more piles, in the kiln.

The furnaces C may be filled at the beginning of the operation, with a sufficient quantity of fuel to burn the bricks, or other articles contained in the chambers,

so that the fire in the kilns will require no attention, except the proper regulation of the draught, by means of the dampers.

I disclaim everything shown and described in the patent of Hoffmann; but

What I claim as new, and desire to secure by Letters Patent, is—

1. In an open-top progressive kiln, the arrangement of bridges B, provided with feed-holes a, substantially as described.

2. The tubular furnaces C, in combination with the burning-chambers A, substantially as set forth.

3. The tubular furnaces C, in combination with the bridges B, extending across the open-top kiln, substantially as described.

This specification signed by me, this 24th day of April, 1869.

HELMUTH DUEBERG.
